J. E. Karel森

UNITED STATES PATENT OFFICE.

J. E. KARELSEN, OF NEW YORK, N. Y.

IMPROVEMENT IN MILLSTONE-DRESSERS.

Specification forming part of Letters Patent No. **36,716**, dated October 21, 1862.

To all whom it may concern:

Be it known that I, J. E. KARELSEN, of the city, county, and State of New York, have invented certain new and useful Improvements in Millstone-Dressers; and I do hereby declare that the following is a full, clear, and exact description of the same, reference being had to the accompanying drawings, forming a part of this specification, in which—

Figure 1 represents a plan or top view of my invention. Fig. 2 is a transverse vertical section of the same.

Similar letters of reference in both views indicate corresponding parts.

This invention consists in the arrangement of a V-shaped guide attached to the front edge of the hinged adjustable rule of a millstone-dress, in combination with a V-shaped lug attached to the edge of the diamond-holder in such a manner that the point of the diamond is prevented falling down into the holes or cavities which inevitably occur in the surface of millstones, and that lines of equal depth can be drawn with ease and facility.

It consists, also, in the application to said rule of one or more serrated spring-catches in such a manner that the operator is prevented from moving the diamond across the surface of the stone in the wrong direction.

It consists, finally, in the arrangement of an adjustable spring-slide in combination with the diamond and its holder in such a manner that the power with which the diamond bears down upon the stone can be regulated, and that said pressure when regulated remains uniform until changed by the operator.

To enable those skilled in the art to fully understand my invention, I will proceed to describe its construction and operation with reference to the drawings.

A represents a flat plate or bed, of cast-iron or any other suitable material, which is provided with three grooves or cavities, *a a' b*. The grooves *a a'* extend in a transverse direction clear across the plate A, and they form the guides for the bars B B', to the front ends of which the rule C is fastened by means of hinges *c*, or in any other convenient manner. Spiral springs *d*, applied to the bars B B', force the same, together with the rule, back in the direction of the arrows marked thereon in Fig. 1, when they are left free to act, or if their action is not opposed.

The central groove, *b*, in the plate A forms the guide for the slide D, which is fastened to the rule C by a hinge, *e*, or by any other suitable means. This slide is furnished on one edge with cogs *f*, meshing into a pinion, *g*, that rotates on a pivot, *h*. To this pinion motion is imparted by an arm, E, which turns on the pivot *h*, and to which a pawl, *i*, is pivoted that gears into a ratchet-wheel, F, attached to said pinion. The pawl *i* is so arranged that by throwing the arm E in the direction of the arrow marked near it in Fig. 1 the ratchet-wheel and pinion are rotated, and in going back said pawl slides over the teeth of the ratchet-wheel, the latter being prevented from turning in the opposite direction by a second pawl, *j*. A spring, *k*, throws the arm E in the direction opposite to the arrow marked on the same, and its motion in this direction is limited by a stop, *k'*, which is adjustable by a set-screw, *l*. By means of this stop the motion of the ratchet-wheel, and, consequently, that of the rule, can be regulated.

The rule C is hinged to the bars B B' D, so that it adjusts itself to the surface of the stone, and its outer edge is provided with a V-shaped projection, *l*, which serves as a guide to the diamond-holder and prevents the diamond sinking down into holes or cavities, that will always exist in the surfaces of stones. One or more serrated spring-bars, G, which are hinged to the upper surface of the rule, prevent the diamond being moved in the wrong direction, they being so arranged that they will open if the diamond-holder is moved in the direction of the arrow marked upon it in Fig. 1; but if it is attempted to start the holder in the opposite direction the serrated bars retain it and prevent its motion.

The diamond-holder H is provided with a V-shaped groove, *m*, fitting in the projection *l* of the rule, and the diamond itself is secured in a head, *n*, which connects by a rod, *o*, with a slide, *p*, being fastened in the same by means of a set-screw, *q*, so that it (the rod) is free to move up and down between certain limits. A spring, *r*, placed between the slide and head, forces the latter, together with the diamond, down, and a set-screw, *s*, which bears upon the end of the slide *p*, allows of adjusting the same up or down, as may be desired. By means of the spring *r* the power with which the diamond bears down upon the stone is

rendered uniform, and this power can be regulated by adjusting the slide *p* up or down by means of the set-screws *s*.

If the diamond is once adjusted it produces lines of uniform depth, and the diamond is prevented being broken by pressing it down on the stone with undue pressure, and if it is desired to produce deeper or shallower lines the set-screw *s* is turned down or up, and thereby the diamond is made to bear on the surface of the stone with greater or less power.

By the use of the hinges *c c e* between the rule *C* and plate *A*, I am enabled to work with the diamond in the interior of the grooves of a millstone, and if the grooves are curved a rule of corresponding shape is inserted, and the dressing can be accomplished with the greatest ease and facility.

Having thus fully described my invention, what I claim as new, and desire to secure by Letters Patent, is—

1. The arrangement of the V-shaped pro-

jection *l* at the front edge of the rule *C*, in combination with a corresponding groove, *m*, on the diamond-holder *H*, constructed and operating substantially as and for the purpose shown and described.

2. The application to the rule *C* of one or more serrated spring-bars *G*, substantially as and for the purpose specified.

3. The arrangement of the adjustable slide *p* and spring *r*, in combination with the head *n*, containing the diamond, and with the set-screws *q* and *s*, and V-shaped groove *m*, all constructed and operating as and for the purpose described.

4. Connecting the rule *C* to the plate *A* by means of hinges *c c e*, or their equivalents, substantially as and for the purpose described.

J. E. KARELSEN.
